PNEUMATIC DISPATCH SYSTEM

Clark T. Cutting, Syracuse, N. Y., assignor to
The Lamson Company, Syracuse, N. Y., a cor-
poration of Massachusetts

Application February 17, 1932. Serial No. 593,527

10 Claims. (Cl. 243—28)

This invention relates to an improvement in pneumatic dispatch systems and more particularly to an improvement in inlet terminals in such systems.

Such inlet terminals are of a push through type wherein the pressure of the head of the carrier to be dispatched opens the inlet valve in contradistinction to the well-known type wherein a clapper valve must be lifted before the carrier to be dispatched can be inserted into the terminal. These inlet terminals may be used in conjunction with outlet terminals as equipment for a receiving and dispatching station which may include either a casing into which carriers are delivered or a flap valve-receiving terminal or may be used independently of a receiving terminal at a station where dispatching alone takes place.

The terminal mechanism includes as well as the valve which normally closes the inlet passage and which is opened by the inserted carrier, a second valve by which air is allowed to escape from or to enter the system concomitantly with the insertion of the carrier, thereby impairing the carrier-transmitting flow of air and also, when desired, introducing into the line a stop which would positively prevent any collision with the inserted carrier.

The objects of this invention are to provide inlet terminals so mounted and constructed that there will be attained the desirable results outlined above, as well as other features which will appear from an examination of the following description and of the drawings which form a part thereof and in which:

Fig. 1 is a side elevation with parts broken away of a carrier-receiving and dispatching station, which includes a casing enclosing the terminals, and which embodies this invention;

Fig. 2 is a longitudinal sectional view of such station;

Figs. 3 and 4 are front and side elevations of the valve of the inlet terminal of such station;

Fig. 5 is a view in elevation with parts broken away of another type of carrier-receiving and dispatching station embodying this invention;

Fig. 6 is a longitudinal sectional view of such station;

Fig. 7 is a view in elevation of a carrier-dispatching station embodying this invention; and

Fig. 8 is a view in elevation of such station taken at right angles to the view shown in Fig. 7.

The various embodiments illustrated in the drawings each comprise a main transmission tube 55 which may be circular in cross section, as in

Figs. 1 to 4, or oval, as in Figs. 5 to 8, and into which carriers are inserted through an inlet or dispatch terminal 11 mounted upon or integral with a station section 12 of the transmission tube 10 and normally closed by a spring-actuated valve 13. The valve 13 is pivotally mounted upon a pin or shaft 14 to swing inwardly under impact of the forward head of the carrier to be dispatched.

The station illustrated in Figs. 1 to 4 inclusive comprises in addition to the inlet or dispatch terminal 13, an outlet or receiving terminal 15 normally closed by a flapper valve 16, here shown, of leather or other flexible material, from which the carriers are discharged into a tray or box 17. The main tube 10 is bent into the form of a U and it, as well as the station section 12 and the outlet terminal, is enclosed by a casing 18 from the bottom of which the tray 17 projects. The carriers designated for such station are deflected from the main tube to the outlet terminal by guide means of any suitable type. The inlet portion of the section 12 bears against the casing 18 in which an opening 20 is formed to permit access to such portion. A guiding flange 21 mounted upon the outer face of the casing facilitates the introduction of the carriers into the inlet terminal.

The valve 13 closes the opening 20 and is held in such position by means of a spring 22 acting upon the shaft 14. In the station section 12 is formed a second opening 23, normally closed by a valve 24. As shown particularly in Figs. 3 and 4, the valves 13 and 24 are carried by arms 25 and 26 respectively, which project from and may be, as here shown, integral with a sleeve 27 through which the shaft 14 is passed. The arms 25 and 26 terminate in plates 28 and 29 respectively, to which the valves 13 and 24 are secured in any suitable manner, the valve 24 being reinforced by a plate 30. Obviously the swinging of the valve 13 into open position by the carrier head causes the valve 24 to open simultaneously and thus provides a direct connection between the transmission tube and the atmosphere and impairs the effective flow of air.

When, as is the usual custom, the carriers are transported by vacuum, the opening of the valves impairs the action of the vacuum upon the carriers approaching the station, so that they come substantially to rest until the inserted carrier has been dispatched and the valves are closed by the spring 22, restoring the system to its operating condition.

The station shown in Figs. 5 and 6 also comprises, in addition to the inlet terminal 11, an

outlet terminal 35 normally closed by a clapper valve 36 and has in the station section 12 an opening 37 normally closed by a valve 38. Suitable means may be provided to guide certain carriers to the outlet terminal, but since such means form no part of the present invention they will not be described herein. The valves 13 and 38 are mounted upon the opposite ends of an angular bracket 40 pivotally supported intermediate its ends upon the shaft 14. A spring 41 connected to one end of the bracket 40 holds the valves in their normal closing position. The carriers are guided through the station section 12 by an inner arcuate wall 42, to which one end of the spring 41 is attached. The end of the bracket 40, which supports the valve 13, terminates in a tongue 43, which when the valve is opened projects into the path of travel of the carriers through the section, a slot 44 being provided in the lower edge of the wall 42 to permit such movement. A guiding flange 45 is mounted upon the section 12 about the carrier opening 43 to assist in the insertion of the carrier.

The insertion of a carrier opens the valve 13 and simultaneously opens the valve 38, thus impairing the transmitting flow of air, as described above, with respect to the embodiment shown in Figs. 1 to 4, but also moves the tongue 43 into the position shown in dotted lines in Fig. 6 so that any collision with the inserted carrier is positively prevented. If, however, at the time the carrier is inserted another carrier is passing through the terminal, the tongue will strike such second carrier so the valve 13 can not be fully opened. When this occurs the operator will, of course, wait until the carrier in transit has passed. The bracket 40 is unbalanced since the portion below the shaft 14 is appreciably heavier than that above the shaft 14 so that the parts will normally assume the full-line position of Fig. 6, even though the spring 41 were omitted.

In Figs. 7 and 8 is illustrated a station embodying this invention at which no carriers are received. As in the other stations the station section 12 has openings 50 and 51, which are normally closed by the valve 13 and a valve 52, respectively. The valves 13 and 51 are mounted upon the ends of a bracket 53 pivotally supported intermediate its ends upon the shaft 14. A tongue 54 at the lower end of the bracket 53 will project through a slot 55 in the guiding wall 56, into the path of travel of the carriers when the valves 13 and 52 are opened by the insertion of a carrier and function in the same way as the tongue 43. A suitable flange 57 upon the section 12 surrounds the opening 50 to guide the insertion of the carriers. The bracket 53, like the bracket 40 of the embodiment shown in Figs. 5 and 6, is unbalanced and the valves are normally closed. While no spring is here shown, it might be provided, if desired, under certain operating conditions.

It will be noted that in each embodiment the inlet valve 13 and the air valve move simultaneously, and that the air valve moves outwardly so that the suction set up in the system, if the carriers are transmitted by vacuum, acts upon the air valve and tends to close it, as well as the inlet valve 13. Hence, the vacuum in the system, as well as the unbalanced condition of the brackets and the spring, closes and holds closed the inlet valve except when such valve is positively opened by the insertion of carriers. Furthermore, since, as pointed out above, the opening of the air valve affects adversely the flow

of the air through the system, more particularly in the case of a vacuum system, the danger of collision between the inserted carriers and those in transit is substantially eliminated.

The station section 12 is shown in the various embodiments as consisting of two suitably joined castings. It will be understood, however, that I am not limited to such castings and that the term "station section" is used herein to designate the portion of the transmission tube at the stations where carriers are dispatched, or are dispatched and received, which portion may be of any desired material or construction.

While certain embodiments of the invention have been shown and described, I am not limited thereto, since other embodiments might be made without departing from the spirit and scope of the invention as set forth in the following claims.

I claim:

1. In a pneumatic dispatch system comprising a transmission tube through which carriers are transmitted by the flow of air set up therein, and an inlet terminal including a station section upon the tube having an inlet passage therein through which carriers are introduced into the transmission tube a valve normally closing said passage, and means operated when said valve is opened to disturb the flow of air in the tube, said means comprising an opening in said station section, a valve normally closing said opening, and connections between said valves by which the valves are positively opened or closed concomitantly.

2. In a pneumatic dispatch system comprising a transmission tube through which carriers are transmitted by the flow of air set up therein, and an inlet terminal including a station section upon the tube having an inlet passage therein through which carriers are introduced into the transmission tube, a valve normally closing said passage, and means operated when said valve is opened to disturb the flow of air in the tube, said means comprising an opening in said station section, a valve normally closing said opening and a pivotally mounted member upon which both said valves are secured and by which both valves are opened or closed concomitantly.

3. In a pneumatic dispatch system comprising a transmission tube through which carriers travel and an inlet terminal including a station section upon the tube having a carrier receiving opening therein and a second opening therein, a valve normally closing the carrier receiving opening, means for normally closing the second opening in the section, and means whereby the opening closing means uncovers the opening concomitantly with the opening of the valve and closes the opening concomitantly with the closing of the valve.

4. In a pneumatic dispatch system comprising a transmission tube through which carriers travel and an inlet terminal including a station section upon the tube having a carrier receiving opening therein and a second opening therein, an inwardly opening valve normally closing the carrier receiving opening, an outwardly opening valve normally closing the second opening, and connections between said valves whereby the valves are moved concomitantly into the opened and closed positions.

5. In a pneumatic dispatch system comprising a transmission tube through which carriers travel and an inlet terminal including a station section upon the tube having a carrier receiving opening therein and a second opening therein, a valve normally closing the carrier receiving opening, a

- second valve normally closing the second opening, a member pivotally mounted intermediate its ends on the station section, to the ends of which said valves are secured, whereby the valves are moved concomitantly into the opened and closed positions, and a tongue on one end of the member which projects into the transmission tube when the valves are opened to prevent the passage of carriers by the inlet terminal at such time. 5 80
- 10 6. In a pneumatic dispatch system comprising a transmission tube through which carriers are transmitted by vacuum created by a flow of air set up in the tube, and an inlet terminal including a station section upon the tube having an inlet passage therein through which carriers are inserted into the transmission tube, a valve normally closing said passage and adapted to be opened inwardly upon the pressure thereon of the head of the carrier so inserted, an opening in the station section, a valve normally closing said opening and adapted to be opened outwardly away from the opening, and means by which the valves move concomitantly. 15 90
- 20 7. In a pneumatic dispatch system comprising a transmission tube through which carriers are transmitted by vacuum created by a flow of air set up in the tube, and an inlet terminal including a station section upon the tube having an inlet passage therein through which carriers are inserted into the transmission tube, a valve normally closing said passage and adapted to be opened inwardly upon the pressure thereon of the head of the carrier so inserted, an opening in the station section, a valve normally closing said opening and adapted to be opened outwardly away from the opening, said second valve when opened being closed by the action of the vacuum in the tube, and means connecting said valves whereby the opening of the first valve by the insertion of a carrier opens the second valve and 100 the closing of the second valve by the vacuum closes the first valve. 25 95
- 30 8. In a pneumatic dispatch system comprising a transmission tube through which carriers are transmitted by vacuum created by a flow of air set up in the tube, and an inlet terminal including a station section upon the tube having an inlet passage therein through which carriers are inserted into the transmission tube, a valve normally closing said passage and adapted to be opened inwardly upon the pressure thereon of the head of the carrier so inserted, an opening in the station section, a valve normally closing said opening and adapted to be opened outwardly away from the opening, and a member pivotally mounted on the station section to which said valves are secured whereby the valves move concomitantly. 35 105
- 40 9. In a pneumatic dispatch system comprising a transmission tube through which carriers are transmitted by vacuum created by a flow of air set up in the tube, and an inlet terminal including a station section upon the tube having an inlet passage therein through which carriers are inserted into the transmission tube, a valve normally closing said passage and adapted to be opened inwardly upon the pressure thereon of the head of the carrier so inserted, an opening in the station section, a valve normally closing said opening and adapted to be opened outwardly away from the opening, a member pivotally 115 mounted intermediate its ends on the station section, and to the ends of which said valves are secured whereby the valves are caused to move concomitantly, and a tongue on said member which projects into the path of travel of carriers through the transmission tube. 45 120
